Inventor:

Norman E. MacCallum,

By Blawattelkirk,

Attorneys.

UNITED STATES PATENT OFFICE.

NORMAN E. MACCALLUM, OF PHOENIXVILLE, PENNSYLVANIA.

FURNACE WALL AND LINING CONSTRUCTION.

Application filed August 13, 1924. Serial No. 731,720.

To all whom it may concern:

Be it known that I, NORMAN E. MACCALLUM, a citizen of the United States, and a resident of Phoenixville, county of Chester, State of Pennsylvania, have invented certain new and useful Improvements in Furnace Wall and Lining Construction, of which the following is a specification, reference being had to the accompanying drawing.

It has been the experience of metallurgists from the remotest times in the smelting and heat treatments of iron and other metals and their ores that the walls and linings of furnaces when exposed to high and variable temperatures, even though the linings be composed of the most refractory materials, are subject to rapid disintegration requiring frequent repairs if not entire new units to replace those rendered totally useless.

Such repairs and replacements add materially to the cost of operating a furnace installation and, therefore, to the cost of the product of a furnace whatever be the nature of its output.

Another serious difficulty with refractories is their expansion, contraction and other deformations due to the alternate heating and cooling of the furnaces brought about periodically by the shut-down for repairs, whether extensive or the contrary. It may be pointed out in illustration that, where exterior plates are used in ordinary furnace construction, particularly so in the case of open hearth furnaces, the refractory material built against the interior face of a plate gradually shrinks away from the plate leaving a space which is a source of danger, since, if molten steel finds its way into the space, it is likely to cut its way on through the plate, thereby causing an expensive loss.

In further explanation it may be stated that refractory linings, as ordinarily constructed and used, become attached to the hearth, and that the shrinkage due to cooling causes contraction in the hearth which pulls the attached protecting refractory material away from the exterior plate, leaving an opening which does not close when the furnace is reheated.

It is the object of my invention to overcome these disadvantages, to preserve the walls and hearth as far as possible, and to protect the exterior plates by means of a metallic strip construction which maintains the contact between the basic wall lining and the exterior plates.

A further advantage of my construction consists in the fact that when the basic lining is kept in contact with the exterior plates, water cooling is made easy and effective. Speaking further in this respect, it may be said that, in certain furnaces such as electric furnaces, an adaptation of my invention would be far more effective than bricks, or the tubular metal containers which I have employed as described in U. S. Letters Patent No. 1,106,725, dated August 11, 1914, for the reasons just mentioned and as will be seen hereinafter.

There are still further advantages which accrue with the use of my improved construction. These consist in considerable economies of time, labor and materials as compared with the requirements for the ordinary construction or for tubular containers. No mortar is necessary with my improved construction and it is evident that much labor will be saved as the use of the metal strips obviates handling a multiplicity of bricks or filling and placing a large number of tubes. It is advisable, however, to use a binder of pitch or tar for the basic material, which may be of an inferior type, such as dolomite instead of the more expensive magnesite. Moreover, as will be seen hereinafter, the lining material may be rammed into place after the steel construction is assembled.

In the accompanying drawing I have illustrated one embodiment of my invention in which Fig. 1 is a transverse cross section of a furnace showing details of my furnace-wall and lining construction. Fig. 2 is a fragmentary view in plan of the metallic portion of the base of the hearth, showing how the construction may be applied. Fig. 3 is a fragmentary horizontal cross section on the line 3-3 of Fig. 1.

A rectangular base plate 1 rests in a horizontal position upon supports 2 which, in the illustration, are shown as I beams but

may be of any type such as channel plates. These supports in turn rest upon fundamental supports, which are also shown as I beams 3, in a longitudinal position. These latter beams finally rest upon a suitable foundation which is not shown. The roof 4 may be composed of silica brick as usual. The furnace walls 5 are provided with exterior binding plates 6 formed of steel or 10 any other suitable material. To the base plate 1 and the exterior binding plates 6 are secured a plurality of metal strips 7 preferably disposed inwardly and upwardly in the manner shown. These metal strips are preferably made with flanges 8 through which rivets 9 may be passed to secure the strips 7 to the binding plates 6 and the base plate 1 in the desired position.

After the metal strips 7 are attached to the base plate 1 and the exterior binding plates 6, the spaces between the strips are filled with basic or neutral material, or a combination of such materials, as desired and as indicated at 10. When attaching the metal strips 7 to the exterior binding plates 6 by means of rivets as shown, it will be found expeditious to begin at the top and attach them in a downward succession. It 20 may also be pointed out that the basic, neutral or combined material should be rammed compactly into place so as to reduce as much as possible the porosity and surfaces exposed to thermal and chemical actions and 25 to force the material against the metallic strips and plates. The commonly used basic refractories are magnesite, dolomite and lime. The neutrals are chromite, bauxite and carbon. The preference of choice is in 40 the order named. These materials should be calcined before being used either in the walls or hearth of the furnace.

When the base of the hearth and the walls have been built up as just described several 45 layers of calcined basic material 11, such as magnesite, may be placed upon the base of the hearth as usual and as shown in the illustrations.

Cooling water may be circulated in 50 troughs 12, the purpose being to cause the water to absorb heat from the exterior binding plates 6 which in turn abstract heat from the basic material 10 in contact with the binding plates. This cooling system 55 should extend to the vicinity of the junction between the silica brick roof 4 and the basic materials of the side walls so that the cooling effect will tend to reduce the harmful action between the basic wall and acid roof. 60 Any other system of cooling may be applied, but the construction shown is very simple and very effective since the basic material is packed against the exterior binding plate, thereby causing the cooling effect

to penetrate into the body of the refractory material.

As mentioned hereinbefore, as in the case of ordinary furnace-wall lining construction linings of refractory material are apt to be pulled away from exterior binding plates, 70 leaving spaces which are sources of serious danger. With my construction as herein described and illustrated, it is evident that the refractory material cannot be pulled away from binding plates and that any shrinkage 75 will occur in the hearth where it is softened by the intense heat.

My improved furnace-wall and lining as hereinbefore described is not limited to any particular type of furnace and may be used in open hearth, electric, copper or any other furnace. The exterior binding plates 6 may be of any size or shape desired. They should be sufficiently strong to carry the strips 7 for holding in place the refractory materials for the lining of the furnace walls and base of the hearth. While the exterior binding plates 6 and metal strips 7 may be composed of steel, any other suitable materials may be employed for either or both. It is apparent that my invention may be installed in various forms to meet particular requirements without departing from the spirit of the invention or the scope of the appended claims.

Having thus described my invention, I claim and desire to protect by Letters Patent of the United States:

1. A furnace comprising walls, exterior binding plates for said walls, a plurality of metal strips secured to and projecting inwardly and upwardly from said binding plates and a refractory material packed between said strips and rammed against said binding plates to prevent separation of the refractory material from said plates incident to shrinkage due to cooling of the furnace.

2. A furnace comprising a hearth, an exterior base plate for said hearth, a plurality of metal strips secured to and projecting inwardly and upwardly from said base plate, and a refractory material packed between said strips and said base binding plate into intimate binding contact with said plate.

3. A furnace wall comprising an exterior plate, metal strips attached to and extending inwardly and upwardly from said plates and a refractory material packed between said strips and said plate in intimate contact with said plate and strips.

4. A furnace comprising walls provided with exterior binding plates, a hearth provided with a base binding plate, a plurality of metal strips secured to and projecting inwardly and upwardly from said binding plates and a refractory material packed between said strips and said binding plates in

intimate contact therewith to prevent accidental spacing of the refractory material from said plates.

5. A furnace wall comprising exterior binding plates, a plurality of spaced metal strips having their inner edges provided with flanges and secured at their flanged portions to said plates, said strips extending

inwardly and upwardly from said binding plates, and a refractory material held together between said strips and said binding plates. 10

In witness whereof, I have hereunto set my hand this 16th day of August, 1924.

NORMAN E. MACCALLUM.
